HAND FAN

Frank H. Klie, deceased, late of Paris, Ill., by
Lillian E. Klie, executrix, Paris, Ill.

Application July 31, 1945, Serial No. 608,035

2 Claims. (Cl. 230—266)

1

The present invention relates to the construction of ordinary hand fans usually consisting of a blade or plate portion and some form of handle, ordinarily a wood stick, fastened thereto. Such fans are extensively used as an advertising medium for free distribution and therefore must be produced at low cost but nevertheless made attractive in appearance and durable in construction.

The main object of this invention is to provide a fan of the class referred to having a lighter, more flexible and more durable handle than the usual stick and one shaped to provide a hand hold wide enough to prevent turning in the hand during use of the fan and comfortable to grasp, all without increasing cost of manufacture.

The foregoing object, as well as other advantages to be hereinafter referred to, is attained by forming the fan handle of light resilient wire and securing it to the fan blade in such a way as to retain flexibility in the handle, reinforce the blade, and prevent either longitudinal or lateral movement of the handle on the blade.

A specific embodiment of the invention is herein described and illustrated in the accompanying drawing, where:

Figure 1 is a rear face view of the fan showing the novel form of handle secured thereto, and

Figure 2 is a sectional face view showing the preferred manner of securing the handle to the fan blade.

In practice of the invention, a handle is formed of a suitable length of light resilient wire bent on itself into the generally "hairpin" form illustrated to provide a looped hand-hold portion 10 and a shank portion 11 consisting of the two arms of the elongated U-shaped member thus formed. Approximately midway of the length of this member the arms are formed with opposed, inwardly extending, V-shaped bends 12 both lying in the same plane and designed to lie against the fan blade 13 adjacent its lower edge, as shown. The shank arms 11 are of such length as to extend to the central portion of the fan blade thereby reinforcing it. The points of the V-shaped notches 12 preferably are extended inwardly and spaced apart as illustrated. The shank arms 11 extend on converging lines to the central portion of the blade and staples 14—15 (Figure 2) have arms 14a—15a extending through the blade and bent over the wires of the shank portion of the handle member to secure it firmly to the blade, certain of the staple arms being

located in the point angles of the V-shaped bends 12.

With the construction described the bends 12 form a narrowed neck in the lower shank portion of the handle member just above the handle proper and adjacent the lower edge of the fan blade 13. This enables a single staple to be used there as a fastening element while retaining the advantage of the wider bearing surface 10 of the shank against the fan blade which can therefore be made of light cardboard. Also, location of fastening elements in the points of the bends 12 provides an effective lock against any movement of the handle member with respect to the blade. The long handle member employed allows the resiliency of the wire to function when the fan is in use, adding to its durability, and the looped handle portion provides a hand-hold which is yielding and comfortable and capable of being firmly held.

The invention claimed is:

1. A fan having a fan blade and a handle member formed of a length of resilient wire bent on itself to form a looped handle portion and shank arms, said arms lying in engagement with the said fan blade, the arms extending on converging lines to the central portion of the blade and being formed with opposed V-shaped bends having the points thereof directed inward, said bends being located adjacent the lower edge of the fan blade, and staples securing the arms to the blade, one of said staples having portions engaging the point angles of the V-shaped bends.

2. A fan having a fan blade and a handle member formed of a length of resilient wire bent on itself to form a looped handle portion and shank arms, said arms lying in engagement with the said fan blade, the arms being formed with opposed V-shaped bends located adjacent the lower edge of the blade, and means for securing the arms of the blade including elements secured to the points of the V-shaped bends.

LILLIAN E. KLINE,
45 Executrix of the Estate of Frank H. Klie, De-
ceased.
